Patented Aug. 13, 1929.

UNITED STATES PATENT OFFICE.

KARL G. ANDERSON, OF ST. PAUL, MINNESOTA, ASSIGNOR TO THE SEEGER REFRIGERATOR COMPANY, A CORPORATION OF MINNESOTA.

REFRIGERATOR.

Application filed January 27, 1921. Serial No. 440,496.

My invention relates to refrigerators and consists of an inner enameled iron shell completely housing the ice and the food to be cooled, with a receptacle for the ice which 5 prevents the ice from being thrown against the inner shell and cracking the enamel.

The invention provides means for attaching the ice receptacle in spaced relation to the inner shell and means for supporting 10 the same and the partition wall between the ice chamber and the food compartment so that said members may be readily removed from the refrigerator for purposes of cleaning.

15 A feature of the invention is to provide a cradle for holding the ice, which consists of a number of slats supported in a group of notched rods hung from the ceiling of the refrigerator.

20 Another feature is to provide a pair of socketed lugs attached to the sides of the refrigerator for holding the several parts of the refrigerator in proper relation to one another.

25 In the drawings forming part of this specification:

Fig. 1 is a vertical sectional view of a refrigerator embodying my invention.

Fig. 2 is a plan sectional view taken on 30 line 2-2 of Fig. 1.

Fig. 3 is a perspective view of the inner shell of the refrigerator.

Fig. 4 is a perspective view of one of the partition members of the invention.

35 Fig. 5 is a part sectional view similar to Fig. 1, showing the method of inserting or removing a section of the partition member.

Fig. 6 is a fragmentary sectional view 40 taken on line 6-6 of Fig. 2.

Fig. 7 is a perspective view of one of the supports for the partition.

My invention is shown as applied to a refrigerator of ordinary construction having 45 a body 10 formed with a double wall consisting of an inner wall 11, an outer wall 12, and an air space 13 completely surrounding the refrigerator on five sides. The front 14 of the refrigerator is made solid except 50 for openings 15, in which are hingedly supported doors of usual construction which

are not shown in the drawings. The entire refrigerator is mounted on legs 16 which have attached to them castors 17.

Within the refrigerator 10 is mounted 55 a single inner shell 18 which occupies the interior of the refrigerator and consists of a back 19, two sides 20 and 21, a top 22, a bottom 23 and a front 24 which follow the surfaces of the inner walls 11. The front 24 is formed with openings 25, 26, and 27 which 60 correspond to the openings 15 in the front wall 14 of the device. The inner shell 18 is best shown in Fig. 3 where the extreme 65 simplicity of the device is brought out. The entire shell may be made in one piece of metal or of sheets of metal riveted or welded together. The entire interior is covered with a vitreous fused enamel which is baked on, making the interior perfectly smooth and 70 eliminating cracks in which dirt and moisture may collect, thereby making the refrigerator perfectly sanitary at all times.

The receptacle for carrying the ice or refrigerating means is best shown in Figs. 75 1 and 2. Across the inner wall member 11 of the top of the refrigerator are positioned two bars 28 and 29, into which are screwed four rods 30, 31, 32 and 33, extending downwardly through holes 35 in the top 22 of 80 the shell 18 and into the interior of the refrigerator. Each of these rods is formed with a shoulder 34 which clamps up against the under side of the top 22 holding said rods firmly attached to and suspended from 85 the interior of the device. With this construction, the rod can be easily detached from the top of the refrigerator. At the ends of rods 30, 31, 32 and 33 the same are held positioned relative to each other by two 90 bars 36 which have their ends 37 and 38 connected to the ends of said rods, nuts 39 are screwed on the ends of said rods to hold 95 bars 36 in place. Swaying of the device is prevented by two lugs 40 and 41 which are formed on two castings, 42 and 43, secured to the walls 19 and 24 of the inner shell by bolts 47, which pass through holes 58 in said walls, as is clearly shown in Fig. 100 5. Rods 30 and 33 pass directly through these lugs and are held from movement by the aforementioned nuts 39, which screw

- up under said lugs and hold the entire receptacle in place. The shelf on which the ice is placed consists of a number of small channel bars 45 which extend across the members 36 and are securely riveted to a pair of flat cross bars 46 which hold them in spaced relation to one another. Where the flanges of channels 45 rest upon bars 36, said flanges are notched so as to prevent the shelf from sliding off of its support, the bottom of said flanges projecting below the tops of bars 36, as is clearly shown in Fig. 1.
- In order to hold the ice in place on top of the ice shelf, the entire space around the ice is enclosed on three sides by means of a number of slats 47 which rest in sockets 48 formed on the previously referred to rods 30, 31, 32 and 33. Said sockets are formed open at the top so that the slats may be easily removed for purposes of cleaning, so that the refrigerator may be kept perfectly sanitary. This construction keeps the ice away from the walls of the inner shell and so prevents injury to the enamel due to careless handling of the ice and furthermore provides a space around the ice through which the air may circulate, thus effecting a more rapid cooling effect and a more even temperature.
- In refrigerators of the type shown it is customary to separate the food chamber from the ice compartment by a division partition wall running across the same but being open at the top and bottom to permit proper air circulation. I have shown such a portion of the louver type which consists of two sections 49 and 50, the former of which is shown in detail in Fig. 4. A number of transverse horizontal louver bars 51 are secured to two upright channel bars 52 and 53 which are placed with their flanges projecting outward and the entire width of each section 49 and 50 is such that these sections just occupy the entire width of the interior of the refrigerator. The lower section 49 is partly supported by the castings 42 which are provided with sockets 54 into which fit projections 55 formed on the webs of channels 52 and 53 by cutting away portions of the flanges at 56.
- In addition to these supports, a pair of channel blocks 57 are employed which are of such size as to pass in between the flanges of channel bars 52 and 53 and which are bolted to walls 19 and 24 of the inner shell 18 by means of bolts 59 which pass through holes 63 in said walls. These blocks are positioned immediately above the sockets 54 and project partly above member 49 when the same is in place so as to form a guide for the following member 50, which rests directly upon member 49.

Another pair of channel blocks 60 are pivotally secured to the walls 19 and 24 of the inner shell by means of bolts 61 which pass through holes 62 in the inner shell. These

members serve to hold the upper partition section 50 in place. In placing the two partitions sections in the refrigerator the lower section 49 is first inserted as shown in Fig. 5, the channel bars 52 and 53 being slid over the channel blocks 60 which are tilted as indicated. When this section has been pushed up towards the top sufficiently so that the lower portion of the same may clear the channel blocks 57, section 49 is swung back to a vertical position and may then be slid down over channel blocks 57, taking the position shown in Fig. 1. Succeeding this operation section 50 is applied in the same manner, the lower portion of this section sliding over the upper part of channel blocks 57 so that the two sections combined form the division partition of the refrigerator. It will be noted that this partition may readily be removed for purposes of cleaning and hence makes the refrigerator perfectly sanitary.

To collect the condensation from the walls of the refrigerator and the water from the ice, I employ a drip pan 63 which comprises two body members 64 and 65 which are held separated from each other to form an air space 66 and which are completely covered by a metal covering 67 which is enameled on the exterior. This drip pan is formed with a raised portion 68 around the edges and is also provided with an outlet 69 through which the water is led into a drain pipe 70 provided with a trap 71 as best shown in Fig. 1. The drain pipe 70 connects with a pipe 72 which is secured to the inner shell 18 of the refrigerator and passes directly through the two walls of the refrigerator to the exterior. The means of supporting the drip pan consist of an angle iron bar 73 which extends directly across the inner shell 18 of the refrigerator between the walls 19 and 24 and is rigidly secured thereto by welding or other suitable means. This drip pan is further supported by the castings 42 and 43 which have sockets 74 formed in them into which two corners of said drip pan extend. A deflector member 75 is welded or otherwise securely fastened to the wall 21 of the inner shell 18 and is bent outward from said wall directing any condensation that may collect on said wall adjacent the ice receptacle directly onto the drip pan, thus keeping the chamber beneath the drip pan dry. Deflector 75, as well as lugs 42 and the other parts of the refrigerator within the inner shell 18, are all enameled for purposes of cleanliness and sanitation.

The advantages of my invention are manifest. An inner shell is provided which may be constructed so as to comprise a single piece with the entire surface covered with an enamel coating. This inner shell surrounds the ice compartment as well as the space for placing the food so that the entire contents of the refrigerator are housed by a

sanitary and impervious closure. All of the parts within the refrigerator are easily demountable so that the same may be scalded and cleaned whenever it is found necessary.

5. The cradle for holding the ice is so arranged as to keep the ice away from the walls of the inner shell, thus preventing any injuries to the same when the ice is deposited upon the ice shelf. A pair of castings serve the triple 10 purpose of partially supporting the ice cradle, drip pan and division partition, holding said members in proper relation to one another.

In accordance with the patent statutes I 15 have described the principles of operation of my invention, together with the apparatus which I now consider to represent the best embodiment thereof, but I desire to have it understood that the construction shown is 20 only illustrative and that the invention can be carried out by other means and applied to uses other than those above set forth within the scope of the following claims:

I claim:

25 1. A refrigerator comprising an inner shell, a plurality of rods supported or hung from the ceiling of said shell in spaced relation to the walls thereof, a shelf secured to the lower ends of said rods, and a plurality 30 of removable slats mounted between said rods to form an inclosure, spaced from the walls of said inner shell.

2. A refrigerator comprising an inner shell, four rods hung from the ceiling of said 35 shell, oppositely facing sockets formed on said rods and a plurality of slats removably positioned in said sockets.

3. A refrigerator comprising an inner shell member, an ice receptacle suspended 40 from the same in spaced relation to the walls thereof, a removable division partition and means for jointly holding said receptacle and partition in spaced relation to each other and the walls of the inner shell.

45 4. A refrigerator having a single interior compartment, a division partition formed with channel edges, socketed members attached to the walls of said refrigerator for receiving the ends of said channel edges and

lugs secured to the walls of said refrigerator 50 over which the said channel edges are adapted to slide in applying the division partition for holding said partition in place.

5. A refrigerator having a single interior compartment, a partition therein made up of 55 a lower section and an upper section, the sides of the sections having channel irons attached thereto, members attached to the walls of the refrigerator having sockets formed therein, said lower section having the 60 lower ends of said channel irons shaped to conform to said socket to be fitted removably therein, a pair of fixed lugs on the walls of the refrigerator, a pair of pivoted lugs aligned with said sockets and said fixed lugs, 65 said fixed lugs removably engaging said channel irons at the top of said lower section and at the bottom of said upper section, said pivoted lugs removably and pivotally engaging said channel irons on the upper 70 end of said upper section.

6. A refrigerator having a single interior compartment, an ice receptacle suspended from the ceiling of said compartment in spaced relation to the walls thereof, a division partition extending across the refrigerator between the front and rear walls, a drip pan positioned below the ice receptacle and a pair of brackets secured to the walls of said inner compartment provided with upwardly 75 extending sockets for supporting the division partition, shelves for partially supporting the drip pan and a pair of lugs for holding the ice receptacle in proper position.

7. A refrigerator comprising a single compartment, a plurality of rods suspended within said compartment in spaced relation to the walls thereof, a number of sockets positioned in said rods having their ends open and extending outwardly from said 80 rods in the direction of the adjacent rods on one side thereof, intermediate sockets formed on said rods having open ends extending outwardly therefrom toward the rods at the other side thereof and at right angles to said 85 first named sockets and slats removably positioned in oppositely facing sockets.

KARL G. ANDERSON.
